UNITED STATES PATENT OFFICE.

SETH WHEELER, OF CASTLETON, NEW YORK.

MACHINE FOR PRODUCING INTERFOLDED PAPER-PACKAGES.

1,393,415.

Specification of Letters Patent. Patented Oct. 11, 1921.

Application filed March 6, 1918. Serial No. 220,759.

To all whom it may concern:

Be it known that I, SETH WHEELER, of Castleton, in the county of Rensselaer, and in the State of New York, have invented a certain new and useful Improvement in Machines for Producing Interfolded Paper Packages; and I do hereby declare that the following is a full, clear, and exact description thereof.

10 The object of my invention has been to provide a machine which shall be capable of cheaply and rapidly forming interfolded paper packages, and to such ends my invention consists in the machine for forming paper packages hereinafter specified.

15 In the drawings—

Figure 1 is a vertical, longitudinal, sectional view of a dispensing cabinet containing a package of paper, such as it is the object of invention of this application to make;

Fig. 2 is a plan view of a blank adapted to be operated on by the machine and practising the process later described, when the blank comprises three double leaves;

Fig. 3 is a side elevation of the blank of Fig. 2 folded;

Fig. 4 is a perspective view of an interfolded package such as made by the machine and process described herein from the blank of Fig. 2, the package being uncollapsed;

Fig. 5 is a view similar to Fig. 4, in which the units are interfolded in a different manner from Fig. 4;

Fig. 6 is a side elevation of a blank similar to that in Figs. 2 and 3, but having only two double leaves;

Fig. 7 is a side elevation of two of the blanks of Fig. 6 interfolded in the manner shown in Fig. 4 to form a package;

Fig. 8 is a side elevation of a machine embodying my invention and adapted to practise the process which forms a part thereof;

Fig. 9 is a front elevation looking in the direction of the arrows of Fig. 8;

Fig. 10 is an enlarged, fragmentary view, with parts in section, of the elements shown in Fig. 8 for operating the folder blades;

Fig. 11 is an enlarged detail section taken on the line 11—11 of Fig. 9;

Fig. 12 is a section taken on the line 12—12 of Fig. 11;

Fig. 13 is a fragmentary detail view of the cutting roller;

Fig. 14 is a plan view of the tucker blade 55 and operating parts therefor;

Fig. 15 is an enlarged fragmentary detail in elevation, showing a wiper blade and its operative parts;

Fig. 16 is a fragmentary cross-section 60 taken on the line 16—16 of Fig. 15;

Fig. 17 is a perspective view of a portion of the detail with hooks and eyes mounted thereon;

Fig. 18 is a fragmentary plan view on an 65 enlarged scale, showing the gripper fingers and means for operating the same;

Fig. 19 is an enlarged section taken on the line 19—19 of Fig. 18;

Fig. 20 is a perspective view of one of the 70 hooks shown in Figs. 18 and 19;

Fig. 21 is a view similar to Fig. 19, showing the parts in a different position;

Fig. 22 is a cross-section on an enlarged 75 scale, taken on the line 22—22 of Fig. 21;

Fig. 23 is a fragmentary plan view with parts removed and parts in section, showing the tapes or belts and adjacent parts, and showing the arms or bails 50 and parts for operating the same;

Fig. 24 is a section taken on the line 24—24 of Fig. 23;

Figs. 25 and 26 are fragmentary elevations of the folder blades and mechanism for operating them, said figures respectively 85 showing the parts in different relations;

Fig. 27 is a section taken on the line 27—27 of Fig. 26;

Fig. 28 is an enlarged view, partly in section, of the tucker blades and the immediate 90 parts carrying and operating them;

Fig. 29 is a cross-section taken on the line 29—29 of Fig. 28;

Fig. 30 is a section taken on the line 95 30—30 of Fig. 31, and showing the locking bar and other operating parts;

Fig. 31 is a fragmentary section partly in section taken on the line 31—31 of Fig. 30;

Fig. 32 is an enlarged view of a portion 100 of the folding cylinders, showing the creasers and co-acting grooves; and,

Figs. 33 and 34 are fragmentary views of parts in section of the follower, Fig. 34 also 105 showing the chute and co-operating parts.

My invention is capable of embodiment in many different forms of machine, and therefore, while I shall illustrate the machine by

those forms which I consider the best embodiments thereof, my invention is not to be limited to the particular forms illustrated, but my claims are to be broadly interpreted.

5 Referring to the drawings, the preferred form of package which it is the object of

the illustrated machine to produce, is one

which, as shown in Fig. 1, is especially

adapted to be delivered from a receptacle

10 preventing access to the contents as a whole and permitting the user to obtain only one

unit at a time, such, for instance, as for the

purpose of delivering towels or toilet paper.

I desire that such package shall always

15 present the units with a doubled or double

edge for the user to take hold of, so that the

user is less likely to tear the unit in with-

drawing it from the receptacle, when his

hands are wet; that such doubled edge shall

20 preferably always project in the same di-

rection from the cabinet, and that the units

shall be so engaged with each other that the

withdrawal of the lowermost unit shall with-

25 certainty cause the doubled or double edge

of the next lowermost unit to project from

the cabinet, and so that the unit shall con-

sist of two sheets fastened together instead

of two separated sheets, either of which

might be dropped to the floor without the

30 other, and shall permit the use of a recep-

tacle having a slight depth horizontally rela-

tive to the size of the sheets of which the

unit is made.

In Fig. 1 I have shown a vertical, sec-

35 tional view of a metal receptacle or cabinet

containing such a package of paper as I

have described, and so arranged that it can

be locked to prevent access to all but the

lowermost unit of the package. The cabi-

30 net 1 has a door 2 which is opened to insert

a package 3 within the cabinet, and is then

locked. The doubled edge 4 of the lower-

most unit of the paper package projects

45 through a slot 5 in the bottom of the recep-

tacle in position for the user to take hold

of it. The package is so made that the

withdrawal of this unit shall cause the cor-

responding doubled edge of the next lower-

50 most unit to project in the same manner so

that the units of the package are brought

within reach one after another, until the

entire package is used up. The blank from

which the preferred form of unit is made is

55 shown in Fig. 2 and consists of a sheet 6

7 and parallel folds 8, 8^a, 9 and 9^a on op-

posite sides of and parallel to the central

fold 7. The blank is folded on the line 7,

thus forming the doubled edge 4, and the

60 folds 8 and 8^a are both made in one direc-

tion, and the folds 9 and 9^a are made in the

opposite direction. The blank thus consists

of the doubled edge 4, connecting leaves 10

and 10^a, intermediate leaves 11 and 11^a, and

65 what may be termed "free" leaves 12 and 12^a.

I preferably interlock the units, as shown in Fig. 4, to form a stack, or pile, or package, by locating the doubled edge 4 of each unit between the free leaves or terminals 12 and 12^a of the next lowermost unit. This dou- 70 bled edge 4 may, however, underlie both of the free leaves 12 and 12^a, as shown in Fig. 5.

A package having the units of the form shown in Figs. 4 and 5 is inserted in the case 75 with the doubled edge 4 of the lowermost unit projecting through the slot, the cabinet being fastened to the wall so that this dou- bled edge projects away from the wall. When the user wishes a unit, he engages the 80 doubled edge and pulls downward. This not only releases the lowermost unit, but draws the doubled edge of the unit above it through the slot so that it projects forward, as did the doubled edge just engaged by the 85 user.

The unit made as shown in Figs. 6 and 7, consists of but four leaves, 13, 13^a, 14 and 14^a, instead of six, as do the units before described, the doubled edge 15 of each unit 90 being located between the leaves 14 and 14^a of the preceding unit. This form of pack- age, however, causes the doubled edges to project alternately in opposite directions, and is therefore less convenient to use than 95 the form before described.

The particular machine which I have illustrated is adapted for making the pack- age shown in Figs. 1, 2, 3 and 4. The said machine comprises frames 16 carrying arms 100 17 that are adapted to support the arbor 18 of a roll of paper 19 from which the units are to be made. A web 20, from the roll of paper 19, is led preferably under a roll 21, and between dividers 22 and a bed roller 23. 105 The web of paper is preferably wide enough to make a series of units side by side, and the dividers 22 are for the purpose of divid- ing the web on longitudinal lines between the proposed units. The cutting edges of 110 the dividers are preferably interrupted at the intervals so as to leave little uncut portions or isthmuses connecting the strips of units to keep the transverse rows of units in line with each other and to prevent some of them 115 getting ahead of others. The roll 21 is shown as mounted in bearings fixed on the frame, and the dividers 22 are shown as mounted in arms 24 that are pivoted at 25 upon brackets carried by the frame, which 120 arrangement permits the dividers to rest against and follow any irregularities in the surface of the bed roller 23. After having been slotted longitudinally by the dividers, the web 20 passes between a cutter cylinder 125 26, and a mashing roll 27, which latter co- operates after the manner of a chopping block with a knife 28 on the cutting cylinder. The knife is shown as being made of rather thin metal and held in place by 130

screws 28^a bearing upon a plate 28^b that rests upon the knife. The mashing roll 27 has a groove 27^a having an edge 27^b that is adapted to coöperate with the knife 28, the groove being deep enough to accommodate the knife. The rolls 21 and 23 preferably have a uniform rate of rotation, but I desire to cause the cutter to travel at a higher rate of speed than the web of paper during the cutting operation, so that it will not only cut the paper, but also move the cut sheet forward and separate it from the web. In cutting very thin paper, the paper, having little stiffness, has a tendency to go with the cutter and fold about it rather than to stand still and be sheared, and thus an ordinary cutter will often not completely sever the sheet. The cutting action such as I have described, however, separates the unsevered portions very successfully. In the present instance, I secure such a cutting action by driving the cutting cylinder 26 from the shaft of the roll 23 by eccentric gears 29 and 30, respectively, mounted on their axes. The mashing roll is preferably driven from the cutting cylinder by ordinary concentric gearing. The eccentric gears are so mounted that the period of accelerated speed of the cutter cylinder occurs while the cutter is in action on the web of paper.

The cutter, of course, does not act until a length of the paper web 20 has been fed past the cutter sufficiently to form a unit. The web, therefore, passes freely between the cutter cylinder 26 and the roll 27, these elements being sufficiently spaced apart for that purpose, and passes between rolls 31 and 32. A series of belts or tapes 33 passes over the upper roller 31 in grooves in the roller, the other ends of the tapes or belts passing over rollers 34. These belts or tapes are provided with hooks 35 which project in a forward direction when on the lower lap of the belt. Grooves or recesses are formed in the lower roll 32 to permit the hooks to pass between the rollers. The web of paper, in passing between the rolls 31 and 32, is consequently engaged by hooks 35, the said hooks being so spaced upon the tapes, and timed by engagement of pins 36 on the upper roller engaging with eyelets 37 on the tapes, that they take hold of the web near its forward end and also in the back portion of the unit severed or to be severed, the unit thus being suspended on the under side of the tapes. The tapes are fed forward continuously.

The unit, severed or to be severed, is carried on by the hooks on the tapes until its forward end stops between upper and lower paper grippers 38 and 39, respectively. The upper gripper 38 is fixedly mounted on a vertically movable carrier 40, and the lower gripper 39 is hinged to the said carrier. A spring

41 bears against the curved under portion of the lower gripper, and normally tends to hold said gripper pressed against the under side of the upper gripper. A pin 42 lies on the upper side of the curved portion of the lower gripper, there being one pin for each of two adjacent pairs of grippers, the pin having collars 42^a thereon to engage with the sides of the grippers and prevent lateral displacement of the pin. A hook 43 is secured to a fixed part of the frame between the pairs of grippers, and a shoulder 44 is likewise secured to the said fixed part some distance below the hook. The carrier 40 is raised and lowered by the action of a lever 45 fulcrumed at 46 on the frame, the lever carrying a roller 47 that rests upon a cam 48. A link 49 is pivoted to the lever and supports the carrier 40, the arrangement being duplicated at both ends of the carrier 40. When the grippers are being raised to their highest position, the pin 42 is engaged by the hook 43, and the said pin, being prevented from rising, acts on the upper curved portion of the lower gripper 39, and holds the said gripper down so that it is separated from the upper gripper, and this is the position while the roller 47 is traveling over a dwell 48^a on the cam. At this time, the hooks on the tapes feed the end of the unit being severed between the grippers. The roller 47, passing off of the dwell 48^a, rides down the cam and lowers the carrier 40 and gripper, drawing the pin 42 away from the hook 43. The pin 42 strikes upon the ledge 44 and being prevented from going lower, the under gripper 39 passes out from engagement with the pin and its spring 41 throws said gripper upward causing it to grip the paper against the under side of the upper gripper. As the grippers continue their descent, they pull the paper down and release it from the adjacent hooks 33^a. At the same time, the paper is released from the rear hooks by an arm or bail 50 that is mounted on a shaft 51, said shaft being oscillated by a rod 52 that is pivoted to a crank 53 mounted with the shaft, the rod 52 being reciprocated longitudinally by the action of a cam 54 on a roller 55 carried on the end of the said rod. A spring 56 on the shaft 51 tends to throw the arm 50 down and to hold the roller 55 against the cam.

Beneath the tapes 33 are a pair of cylinders 57 and 58 which are provided with creasers 59, there being a coöoperating groove 60 in the opposing cylinder for each creaser. These cylinders are provided with air holes 61 in their surfaces and pipes 62 communicate with the interior of the cylinders through the journals, said pipes being connected with any convenient suction apparatus. The journals and cylinders are cut out so that the cylinders rotating on the

- journals only permit communication between the interior of the cylinders and the suction pipes in certain phases of rotation of the cylinders. This suction is for the purpose of holding the ends, or free leaves 12 and 12^a of the units to the surfaces of the cylinders until the doubled edge of the next succeeding unit is inserted between them, as later described. A tucker blade 63 is mounted in any desired way to make the middle fold 7 of the unit by thrusting the blade against the unit from above and folding it between the two cylinders 57 and 58. In the present instance, the tucker blade is mounted on arms 64 that are secured to a shaft 64^a carrying a crank 65, which crank is connected by a link 66 with a bar 67, said bar having a slot in its forward end which slides on a fixed pin 68, and being operated at its rear end by a cam 69, the reciprocation of the bar causing the link 66 to reciprocate the crank 65, and thus to oscillate the arm 64 and raise and lower the tucker blade. A spring 64^b on the crank shaft tends to throw the tucker blade down when the cam will permit it.
- The grippers hold the forward end of the blank unit so that the tucker strikes the unit at a definite distance from its forward end, the slack all coming from the rear end of the unit or that end toward the cutter, and thus the middle fold 7 is formed in exactly the desired place. If the slack came from both ends, it could never be told with certainty how the slack would be divided, and consequently where the fold would be made. The tucker blade being mounted as it is, not only has an up-and-down movement, but has a component in the direction from the grippers toward the center of the unit. This component of the tucker blade's motion tends to take out any slack between the grippers and the center of the unit, and to insure that all the slack shall come from the other end of the unit. The downward movement of the grippers and of the finger 50 carries the paper down against the surface of the cylinders 57 and 58, so that the suction can take hold of the paper.
- In order to keep the rear edge of the sheet in close contact with the rear creasing cylinder 58, I provide fingers 69^a mounted on a shaft 69^b, the latter carrying a crank 69^c, the fingers being preferably provided with rubber or other friction pads 69^d. The shaft is oscillated by engagement of a cam 69^e with a roller 69^f on a lever 69^g, which latter is connected with the crank 69^c by a link 69^h, a spring 69ⁱ tending to retract the fingers from the cylinder and to hold the roller 69^f against the cam.
- The unit carried down by the tucker blade is caught between the cylinders 57 and 58, and the folds or creases 8 and 9 are made in opposite sides of the unit by the creases 59 co-operating with the grooves 60. As the unit descends, the suction is "admitted" (so to speak) to the interior of the cylinders, and the free leaves 12 and 12^a of the unit are "sucked" against the surfaces of the cylinders holding them apart, a new unit being meanwhile brought into position and tucked between the said free leaves as they are closed together by the action of the cylinders.
- I desire to provide means to fold the units into the zig-zag shape shown in Fig. 4, in which the folds 8 and 9 will be projected in opposite directions, and to collapse the continuous chain of units into a package in the condition shown in Fig. 1. Such means, in the present instance, consists of folder blades 70 and 71 which project horizontally from opposite directions. Each blade is mounted on a slide 72 that is vertically movable on a base 73, the latter being formed on, or attached to, a horizontally movable slide 74. Means for reciprocating the slides 74 are shown in the present instance as consisting of a rack 75 carried by the said slide, which rack is engaged by a pinion 76 that rolls on a stationary rack 77. The pinions 76 carry links 78 which are pivoted together and to a link 79, the said link being pivoted to one arm of a lever 80 whose opposite arm is connected by a link 81 with a crank pin 82. This mechanism causes the link 79 to rise and fall, and to spread apart the links 78 like a toggle joint, causing the pinions to travel on the stationary racks 100 and thus to force the racks 75 back and forth on the horizontally movable slides 74, and to give horizontal movement to the folder blades 70 and 71.
- I desire to draw the folder blades back alternately and to lock the one not to be drawn back from horizontal movement. For that purpose I provide vertically movable bolts 83 that have rack teeth formed thereon, which teeth engage pinions 84 mounted on fixed journals. The pinions 84 are secured to pinions 85 that engage horizontal rack teeth 86 carried by a bar 87, said bar carrying anti-friction rollers 88 that engage the opposite edges of a cam 89. The said cam reciprocates the bar 87, causing the pinions 84 to rotate, and these pinions throw the bolts 83 up and down alternately, the bolt being thrown up which corresponds with the folder blade which it is desired to hold stationary. The holding of one of the folder blades stationary, say, the right-hand one, as seen in Fig. 26, prevents movement of its slide 74 and consequently of its rack 75, and thus its pinion 76 is held from movement, and all the motion due to the straightening of the toggle joint formed by the two links 78, is given to the opposite pinion 75.

(the left-hand one in the supposed example), and the left-hand folder blade is thus withdrawn.

I desire to give the folder blades a vertical, as well as a horizontal movement, and for that purpose the vertically movable slides 72 carry anti-friction rolls 90 which engage slots 91 in L-shape plates 92. These plates have slots 92^a which engage pins 93 on the frame, and the upper ends of the said plates 92 are pivoted to levers 94 that are fulcrumed on a stationary pin 95, the levers having anti-friction rolls 96 that rest upon cams 97. The cams 97 are so shaped, and the mechanism for moving the folder blades horizontally and for locking them, is so proportioned that, as shown in Fig. 10, for instance, the folder blade 70 is first thrown forward to fold the leaves 10^a and 11^a against each other, and to form the folds 8—8^a and then the folder blade 71 is thrown toward the unit to form the folds 9—9^a, and to bring the leaves 11 and 12 toward each other. The folder blades not only form the folds described, but press downward on the leaves underneath them, each one alternately holding the stack of units beneath it in a compressed condition, while the other folder blade is withdrawn from beneath that one which is holding the stack, and is then thrust forward above it to perform its operation, and in its turn to hold the said stack down while the first mentioned folder blade repeats its operation. The motion of the folder blades is like that of children's hands when they play a game in which one child places its hands upon the table and another child slaps its hand upon that of the child who first played, and then the child who first played withdraws his hand from beneath and places his upon the top again, and so on.

The stack of collapsed units is compressed into a receptacle which, in the present instance, is shown as a chute 98. When the machine is first started, it is desirable to provide some form of resistance for the stack of collapsed interleaved units in the chute until the chute has been filled or is sufficiently filled so that the friction of the stack on the sides of the chute will afford such resistance. I have accordingly provided a follower 99 which carries an arm 100 that is provided with a split bearing 101, and this arm 100 is frictionally engaged upon a shaft 102 of a pinion 103, by drawing the split bearing together by means of a bolt 104 and thumb nut 105. The pinion engages a rack 106 on the chute so that the follower can only slide down the chute by the travel of the pinion along the rack, and this travel is resisted by the friction of the shaft 102 in the arm 100.

In describing the illustrated embodiment of my invention, I have described the op-

eration of the mechanism as I have described the successive parts of the mechanism. It is therefore not necessary to describe the operation in detail. The general operation of the machine may thus be briefly stated. The web of paper 20 on the roll 19 passes through the cutting and dividing mechanism, and is cut into rows of units, each row, as it passes between the cylinders 31 and 32, being impaled upon the hooks 35 on the belts 33, and being carried on the under side of the said belts to a position over the folding cylinders 57 and 58. In this position, the front edge of the units is between the pairs of grippers 38 and 39. The grippers engage the front edge and descend, and at the same time the arm 50 descends, and thus the unit is released from the hooks and brought down into contact with the surfaces of the cylinders and within reach of the suction from within them. The tucker blade 63 descends, tucking the unit between the cylinders, and taking all the slack from the right hand end, as seen in Fig. 11, since the grippers hold their edge of the unit with a grip which, though yielding when the cylinders have gotten a grip on the doubled edge of the unit, is positive as compared to any resistance on the right hand end of the unit. Thus it can be told with certainty where to position the grippers so that the unit will be centrally folded. The suction holds the free edges or leaves of the unit against the cylinders, so that they are open when a succeeding unit is formed, and ready to receive the doubled edge of such succeeding unit, the units thus, in effect, forming a web. The units are creased parallel to the doubled edge by the blades 59, co-operating with the grooves 60, so that they assume a more or less zig-zag form as they pass from between the cylinders. The folders 70 and 71 are alternately thrust into the V-shape recesses of the paper formed by the creases, and press down on the leaf or fold underneath and hold it down while the other folder is thrust in above the fold immediately over the first mentioned folder and pressed down. After the second mentioned folder has gotten a stack of collapsed web or units under its control, the first mentioned folder is drawn back, raised and again thrust forward to engage another section of the web. The stack of collapsed units thus accumulates in the chute, and the follower which is inserted when the machine is empty is gradually forced down to the end of the chute and taken out, the friction of the walls of the chute thereafter affording sufficient resistance to the downward movement of the folded units.

I claim:

1. In a machine of the class described, the combination of means for folding successive

- sheets or units, and means for so holding each sheet or unit that the edge of the succeeding unit shall be placed between and in contact with the free edges or leaves of the 5 first mentioned unit.
2. In a machine of the class described, the combination of means for successively severing sheets or units from a strip, means for successively folding said units, and means 10 for holding each unit so that the doubled edge of the succeeding unit shall be placed between and in contact with the free leaves or edges of said first mentioned unit.
3. In a machine of the class described, the 15 combination of means for successively severing sheets or units from a strip, means for successively folding said units, means for holding each unit so that the doubled edge of the succeeding unit shall be placed between the free leaves or edges of said first mentioned unit and means for scoring or 20 creasing each unit parallel to its doubled edge.
4. In a machine of the class described, the 25 combination of means for successively severing sheets or units from a strip, means for successively folding said units, means for holding each unit so that the doubled edge of the succeeding unit shall be placed between the free leaves or edges of said first 30 mentioned unit, and means for scoring or creasing each unit parallel to its doubled edge with a plurality of oppositely facing scores or creases.
5. In a machine of the class described, the 35 combination of means for successively severing sheets or units from a strip, means for successively folding said units, means for holding each unit so that the doubled edge of the succeeding unit shall be placed between the free leaves or edges of said first 40 mentioned unit, means for scoring or creasing each unit parallel to its doubled edge with a plurality of oppositely facing scores or creases, and means for collapsing the train 45 of units to form a package.
6. In a machine of the class described, the 50 combination of means for successively severing sheets or units from a strip, means for successively folding said units, means for holding each unit so that the doubled edge of the succeeding unit shall be placed between the free leaves or edges of said first 55 mentioned unit, means for scoring or creasing each unit parallel to its doubled edge with a plurality of oppositely facing scores or creases, and means for collapsing the train of units to form a package, said means 60 engaging the scores or creases and forcing them in opposite directions relative to the plane of the sheet or unit.
7. In a machine of the class described, the 65 combination of a pair of parallel cylinders whose adjacent surfaces are close to each other, means for feeding a sheet or unit over the space between said cylinders, means for doubling and forcing said unit between said cylinders, and means for grasping one edge of said sheet or unit while the latter is being tucked between said cylinders. 70
8. In a machine of the class described, the combination of a pair of parallel cylinders whose adjacent surfaces are close to each other, means for feeding a sheet or unit over the space between said cylinders, means for 75 doubling and forcing said unit between said cylinders, and means for yieldingly grasping one edge of said sheet or unit while the latter is being tucked between said cylinders.
9. In a machine of the class described, the 80 combination of a pair of parallel cylinders whose adjacent surfaces are close to each other, means for feeding a sheet or unit over the space between said cylinders, means for doubling and forcing said unit between said 85 cylinders, means for holding one edge of said sheet or unit while the latter is being tucked between said cylinders, and means for causing the free edges or leaves of a sheet or unit to lie upon the surfaces of said 90 cylinders.
10. In a machine of the class described, the combination of a pair of parallel cylinders whose adjacent surfaces are close to each other, means for feeding a sheet or unit over the space between said cylinders, means for doubling and forcing said unit between said 95 cylinders, means for yieldingly holding one edge of said sheet or unit while the latter is being tucked between said cylinders, and means for causing the free edges or leaves of a sheet or unit to lie upon the surfaces of said 100 cylinders.
11. In a machine of the class described, the combination of a pair of parallel cylinders whose adjacent surfaces are close to each other, means for feeding a sheet or unit over the space between said cylinders, means for doubling and forcing said unit between said 105 cylinders, means for holding one edge of said sheet or unit while the latter is being tucked between said cylinders, and means for causing the free edges or leaves of a sheet or unit to lie upon the surfaces of said cylinders.
12. In a machine of the class described, the combination of a pair of parallel cylinders whose adjacent surfaces are close to each other, means for feeding a sheet or unit over the space between said cylinders, means for doubling and forcing said unit between said 110 cylinders, means for yieldingly holding one edge of said sheet or unit while the latter is being tucked between said cylinders, and pneumatic means for causing the free edges or leaves of a sheet or unit to lie upon the surfaces of said cylinders. 115
13. In a machine of the class described, the combination of a pair of parallel cylinders whose adjacent surfaces are close to each other, means for feeding a sheet or unit over the space between said cylinders, means for doubling and forcing said unit between said 115 cylinders, means for yieldingly holding one edge of said sheet or unit while the latter is being tucked between said cylinders, and pneumatic means for causing the 120 free edges or leaves of a sheet or unit to lie upon the surfaces of said cylinders.
14. In a machine of the class described, the combination of a pair of parallel cylinders whose adjacent surfaces are close to each other, means for feeding a sheet or unit over the space between said cylinders, means for doubling and forcing said unit between said 125 cylinders, means for yieldingly holding one edge of said sheet or unit while the latter is being tucked between said cylinders, and pneumatic means for causing the free edges or leaves of a sheet or unit to lie upon the surfaces of said cylinders.

- each other, means for feeding a sheet or unit over the space between said cylinders, means for doubling and forcing said unit between said cylinders, means for holding one edge 5 of said sheet or unit while the latter is being tucked between said cylinders, and pneumatic means acting by suction for causing the free edges or leaves of a sheet or unit to lie upon the surfaces of said cylinders. 70
- 10 14. In a machine of the class described, the combination of a pair of parallel cylinders whose adjacent surfaces are close to each other, means for feeding a sheet or unit over the space between said cylinders, means for doubling and forcing said unit between said cylinders, means for yieldingly holding one edge of said sheet or unit while the latter is being tucked between said cylinders, and pneumatic means acting by suction for causing the free edges or leaves of a sheet or unit to lie upon the surfaces of said cylinders. 75
- 15 15. In a machine of the class described, the combination of a pair of parallel cylinders, whose adjacent surfaces are close together, means for feeding a sheet or unit over the space between said cylinders, means for tucking said unit into said space, said parts being so timed that the second unit 80 shall be tucked between the free leaves or edges of said first mentioned unit before said free leaves or edges have been closed upon each other. 85
- 20 16. In a machine of the class described, the combination of a pair of parallel cylinders whose adjacent surfaces are close to each other, means for tucking successive units between said cylinders, means for holding the free leaves or edges of each unit 90 open until the doubled edge of the succeeding unit shall have been placed between the free leaves or edges of the unit first mentioned, and means for creasing each unit parallel to its doubled edge. 95
- 25 17. In a machine of the class described, the combination of a pair of parallel cylinders whose adjacent surfaces are close to each other, means for tucking successive units between said cylinders, means for holding the free leaves or edges of each unit 100 open until the doubled edge of the succeeding unit shall have been placed between the free leaves or edges of the unit first mentioned, and means for creasing each unit parallel to its doubled edge. 110
- 30 18. In a machine of the class described, the combination of a pair of parallel cylinders whose adjacent surfaces are close to each other, means for tucking successive units between said cylinders, means for holding the free leaves or edges of each unit 115 open until the doubled edge of the succeeding unit shall have been placed between the free leaves or edges of the unit first mentioned, and means for creasing each unit parallel to its doubled edge. 120
- 35 19. In a machine of the class described, the combination of a pair of parallel cylinders whose adjacent surfaces are close to each other, means for tucking successive units between said cylinders, means for holding the free leaves or edges of each unit 125 open until the doubled edge of the succeeding unit shall have been placed between the free leaves or edges of the unit first mentioned, means for creasing each unit parallel to its doubled edge, there being a plurality of oppositely directed creases formed in each unit parallel to its opposite edge. 130
- 40 20. In a machine of the class described, the combination of a pair of parallel cylinders whose adjacent surfaces are close to each other, means for tucking successive units between said cylinders, means for holding the free leaves or edges of each unit open until the doubled edge of the succeeding unit shall have been placed between the free leaves or edges of the unit first mentioned, means for creasing each unit parallel to its doubled edge, there being a plurality of oppositely directed creases formed in each unit parallel to its opposite edge, and means to engage said creases to collapse the units to form a package. 140
- 45 21. In a machine of the class described, the combination of two parallel cylinders, means for feeding a sheet or unit over the space between said cylinders, means for successively tucking the units into said space, means for holding the free leaves or edges of each unit open until the doubled edge of the succeeding unit shall have been tucked therebetween, and a blade on one of said cylinders adapted to form a crease in a unit parallel to its doubled edge. 150
- 50 22. In a machine of the class described, the combination of two parallel cylinders, means for feeding a sheet or unit over the space between said cylinders, means for successively tucking the units into said space, means for holding the free leaves or edges of each unit open until the doubled edge of the succeeding unit shall have been tucked therebetween, and a plurality of blades on said cylinders adapted to form creases in said units parallel to their doubled edges, the blades being alternately mounted upon opposite cylinders. 160
- 55 23. In a machine of the class described, the combination of two parallel cylinders, means for feeding a sheet or unit over the space between said cylinders, means for successively tucking the units into said space, means for holding the free leaves or edges of each unit open until the doubled edge of the succeeding unit shall have been placed between the free 170

- of each unit open until the doubled edge of the succeeding unit shall have been tucked therebetween, a plurality of blades on said cylinders adapted to form creases in said units parallel to their doubled edges, the blades being alternately mounted upon opposite cylinders, and folding means adapted to engage each of said creases and collapse the units.
- 10 24. In a machine of the class described, the combination of two parallel cylinders, means for feeding a sheet or unit over the space between said cylinders, means for successively tucking the units into said space,
- 15 means for holding the free leaves or edges of each unit open until the doubled edge of the succeeding unit shall have been tucked therebetween, a plurality of blades on said cylinders adapted to form creases in said units parallel to their doubled edges, the blades being alternately mounted upon opposite cylinders, oppositely disposed folding blades adapted to engage said creases, and means for giving said folding blades,
- 20 both a motion in their own planes and a lateral motion of transition.
- 25 In a machine of the class described, the combination of a pair of parallel cylinders whose adjacent surfaces are close to each other, means for feeding a sheet or unit over the space between said cylinders, means for exhausting air from said cylinders, means for depressing said unit against the surfaces of said cylinders to insure engagement by said suction, and means for tucking the unit into the space between said cylinders.
- 30 26. In a machine of the class described, the combination of a pair of parallel cylinders whose adjacent surfaces are close together, means for exhausting air from within said cylinders, means for cutting a sheet or unit from a strip, means for engaging said unit from the face opposite to said cylinders, and for transporting it over said cylinders, and means for engaging said unit to disengage it from said last mentioned means and bring it into contact with said cylinders.
- 35 27. In a machine of the class described, the combination of a pair of parallel cylinders whose adjacent surfaces are close together, means for exhausting air from within said cylinders, means for cutting a sheet or unit from a strip, means for engaging said unit from the face opposite to said cylinders, and for transporting it over said cylinders, and a plurality of means for engaging said unit to disengage it from said last mentioned means and bring it into contact with said cylinders, one of said disengaging means being adapted to engage and yieldingly hold one edge of said unit.
- 40 28. In a machine of the class described,
- 45 the combination of a pair of parallel cylinders whose adjacent surfaces are close together, means for exhausting air from within said cylinders, means for cutting a sheet or unit from a strip, means for engaging said unit from the face opposite to said cylinders, and for transporting it over said cylinders, a plurality of means for engaging said unit to disengage it from said last mentioned means and bring it into contact with said cylinders, one of said disengaging means being adapted to engage and yieldingly grasp one edge of said unit, and means adapted to tuck the unit between said cylinders.
- 50 29. In a machine of the class described, the combination of a pair of parallel cylinders whose adjacent faces are close to each other, means for severing a blank from a strip, a belt or belts having hooks projecting from their faces, means for feeding the unit against said belt so that said hooks shall engage said unit, said belts being so located as to carry the unit over the space between said cylinders.
- 55 30. In a machine of the class described, the combination of a pair of parallel cylinders whose adjacent faces are close to each other, means for severing a blank from a strip, a belt or belts having hooks projecting from their faces, means for feeding the unit against said belt so that said hooks shall engage said unit, said belts being so located as to carry the unit over the space between said cylinders, and means for disengaging said unit from said hooks and bringing it in contact with the cylinders.
- 60 31. In a machine of the class described, the combination of a pair of parallel cylinders whose adjacent faces are close to each other, means for severing a blank from a strip, a belt or belts having hooks projecting from their faces, means for feeding the unit against said belt so that said hooks shall engage said unit, said belts being so located as to carry the unit over the space between said cylinders, and means for engaging each end of said unit to disengage it from the belt or belts and press it against the surface of the cylinders, one of said engaging means being adapted to engage and yieldingly hold the forward edge of the blank.
- 65 32. In a machine of the class described, the combination of means for doubling successive sheets or units, means for interleaving such units so as to form a continuous web of doubled units, means for oppositely creasing said web, a receptacle, and means for collapsing said web into said receptacle.
- 70 33. In a machine of the class described, the combination of means for doubling successive sheets or units, means for interleaving such units so as to form a continuous web

- of doubled units, means for oppositely creasing said web, a chute, and means for collapsing said web into said chute.
34. In a machine of the class described, the combination of means for doubling successive sheets or units, means for interleaving such units so as to form a continuous web of doubled units, means for oppositely creasing said web, a chute, and means for collapsing said web into said chute, said chute being provided with a yielding follower to yieldingly resist the packing of said web into the chute. 70
35. In a machine of the class described, the combination of means for doubling successive sheets or units, means for interleaving each unit with the preceding one by engagement of the doubled edge of one with the free edges or leaves of the other, so as to form a continuous web of units, a receptacle, and folders adapted to engage said web alternately on opposite sides, and then to move the engaged portion toward the receptacle and to hold it there until the other folder has reached a similar position. 80
36. In a machine of the class described, the combination of means for folding successive sheets or units, and for interleaving the folded edge of each unit with the free edges or leaves of the preceding unit, means for creasing said web alternately on opposite sides, a receptacle, and folders adapted to alternately engage sections of said web between said creases, and to move said sections toward said receptacle. 85
37. In a machine of the class described, the combination of means for folding successive sheets or units, and for interleaving the folded edge of each unit with the free edges or leaves of the preceding unit, means for creasing said web alternately on opposite sides, a receptacle, and folders adapted to alternately engage sections of said web between said creases, and to move said sections toward said receptacle, the operating means of said folders being also so constructed as to withdraw a folder after the other folder has been brought into position to hold the stack of collapsed units. 90
38. In a machine of the class described, the combination of means for severing a sheet or unit from a web and for presenting it between a pair of rollers, a belt passing over the upper of said pair of rollers and provided with spurs or hooks to engage the unit, a pair of folding cylinders, and means to engage both ends of said unit to remove it from said spurs or hooks and to place it against said folding cylinders. 100
39. In a machine of the class described, the combination of a pair of folding cylinders, means for placing a sheet or unit in position to be folded between said cylinders, means for yieldingly grasping one edge of said unit, and a tucker to tuck said unit between said cylinders, the direction of motion of said tucker having a component away from said yielding grasping means toward the location of the fold to be formed 105
40. In a machine of the class described, the combination of a pair of folding cylinders, means for placing a sheet or unit in position to be folded between said cylinders, means for yieldingly grasping one edge of said unit, and a tucker to tuck said unit between said cylinders, said tucker swinging about a center not substantially removed from the plane of the axes of said cylinders. 110
41. In a machine of the class described, the combination of a pair of folding cylinders, means for positioning a sheet or unit near said cylinders, said means engaging the unit from the side opposite said cylinders, and grippers so constructed as to yieldingly engage an edge of the unit and move such edge toward said cylinders. 115
42. In a machine of the class described, the combination of means for forming a continuous web of interleaved units, and means for folding said web into packages, comprising slides mounted to move substantially perpendicularly to the web, slides mounted on said first mentioned slides to move substantially parallel to said web, said last mentioned slides carrying folders, and means to so actuate each of said slides that said folders shall alternately approach and recede from the web and move vertically, said means for moving said horizontal slides comprising means to move the horizontal slides toward and from each other, and means adapted alternately to lock one horizontal slide from motion, and then the other from motion. 120
43. In a machine of the class described, the combination of means for forming a continuous web of interleaved units, means for folding said web into packages, comprising slides mounted to move substantially perpendicularly to the web, slides mounted on said first mentioned slides to move substantially parallel to said web, said last mentioned slides carrying folders, and means to so actuate each of said slides that said folders shall alternately approach and recede from the web and move vertically, comprising racks on said horizontal slides, pinions engaging said racks, and stationary racks also engaged by said pinions, and means for moving said pinions toward and from each other. 125
44. In a machine of the class described, the combination of means for forming a continuous web of interleaved units, means for folding said web into packages, comprising slides mounted to move substantially perpendicularly to the web, slides mounted on said first mentioned slides to move substantially parallel to said web, said last men- 130

- tioned slides carrying folders, and means to so actuate each of said slides that said folders shall alternately approach and recede from the web and move vertically, 5 comprising racks on said horizontal slides, pinions engaging said racks, and stationary racks also engaged by said pinions, means for moving said pinions toward and from each other, and means adapted alternately to lock one horizontal slide from motion and then the other from motion.
45. In a machine of the class described, the combination of means for forming a continuous web of interleaved units, means for 10 folding said web into packages, comprising slides mounted to move substantially perpendicularly to the web, slides mounted on said first mentioned slides to move substantially parallel to said web, said last mentioned slides carrying folders, and means to so actuate each of said slides that said folders shall alternately approach and recede from the web and move vertically, comprising racks on said horizontal slides, pinions engaging said racks, and stationary racks also engaged by said pinions, means for moving said pinions toward and from each other, and means adapted alternately to lock one horizontal slide from motion and then the other from motion, said means for moving said pinions toward and from each other comprising a toggle joint connecting said pinions, and means to actuate the middle joint of the toggle.
35. 46. In a machine of the class described, the combination of a pair of parallel folding cylinders, means to present a sheet or unit to said cylinders, means to tuck said unit between said cylinders, said cylinders having 15 perforations in their peripheries, means to exhaust air from within said cylinders, and means to control said exhaust so that it will only operate at particular times.
47. In a machine of the class described, 20 the combination of a pair of parallel folding cylinders, means to present a sheet or unit to said cylinders, means to tuck said unit between said cylinders, said cylinders having perforations in their peripheries, means to exhaust air from within said cylinders, and means to control said exhaust so that it will only operate at particular times, said 25 exhaust controlling means comprising hollow journals for said cylinders, which journals are connected with the exhaust means, and ports in the cylinders and journals.
48. In a machine of the class described, the combination of means for forming a continuous web of interleaved units, and 30 means for folding said web into packages, comprising a pair of slides mounted to move substantially parallel to said web, a pair of slides mounted to move substantially vertically to said web, said last mentioned slides carrying folders, one slide of each pair being 35 mounted on the corresponding slide of the other pair, and means to so actuate each of said slides that said folders shall alternately approach and recede from the web and move vertically.
49. In a machine of the class described, the combination of a pair of parallel cylinders, whose adjacent surfaces are close to each other, means for feeding a sheet or unit over the space between said cylinders, means for exhausting air from said cylinders, means for compressing the body of the sheet toward said cylinders, and means for engaging both edges of the sheet to insure engagement by said suction.
50. In a machine of the class described, the combination of a pair of folding cylinders, means for placing a sheet or unit in position to be folded between said cylinders, said means engaging the unit from the side opposite the cylinders, means for disengaging the sheet from said last mentioned means, and fingers adapted to engage an edge of said sheet and hold it against the surface of one of said cylinders.
51. In a machine of the class described, the combination of a pair of folding cylinders, means for placing a sheet or unit in position to be folded between said cylinders, said means engaging the unit from the side opposite the cylinders, means for disengaging the sheet from said last mentioned means, and fingers adapted to engage an edge of said sheet and hold it against the surface of one of said cylinders, said fingers being provided with a friction surface toward the paper.
52. In a machine of the class described, the combination of a pair of folding cylinders, means for placing a sheet or unit in position to be folded between said cylinders, said means engaging the unit from the side opposite the cylinders, means for disengaging the sheet from said last mentioned means, fingers adapted to engage an edge of said sheet and hold it against the surface of one of said cylinders, said fingers being pivoted, and means for periodically moving said fingers toward the surface of said cylinder.
53. In a machine of the class described, the combination of means for severing a sheet or unit from a web and for presenting it between a pair of rollers, a belt passing over the upper of said pair of rollers, and provided with spars or hooks to engage the unit, said roller being provided with pins or teeth to engage said belt against slipping, a pair of folding cylinders, and means to engage both ends of said unit to remove it from said spars or hooks and place it against said folding cylinders.
54. In a machine of the class described, the combination of means for severing a sheet or unit from a web and for presenting it

it between a pair of rollers, a belt passing over the upper of said pair of rollers, and provided with spurs or hooks to engage the unit, said roller being provided with 5 pins or teeth to engage said belt against slipping, a pair of folding cylinders, means to engage both ends of said unit to remove it from said spurs or hooks and place it

against said folding cylinders, and means for turning said roller continuously. 16

In testimony that I claim the foregoing I have hereunto set my hand.

SETH WHEELER.
